UNITED STATES PATENT OFFICE.

EDWIN LICHTENSTEIN, OF NEW YORK, N. Y.

FEEDING DEVICE FOR IRONING-MACHINES.

1,267,779.

Specification of Letters Patent. Patented May 28, 1918.

Application filed August 5, 1916. Serial No. 113,282.

To all whom it may concern:

Be it known that I, EDWIN LICHTENSTEIN, citizen of the United States, residing at New York, in the county of New York and State 5 of New York, have invented certain new and useful Improvements in Feeding Devices for Ironing-Machines, of which the following is a specification.

This invention relates to ironing machines, and more particularly to devices for use in feeding the work to flat work ironing machines. Such machines are employed for ironing sheets, table cloths and like flat articles of various sizes, which articles are 15 usually fed to the machine by one or two operators from bars or horses upon which they are previously arranged.

The particular objects of this invention are to reduce the necessary work or effort 20 of the operators, who heretofore have been required to lift or move loaded bars or horses, whereas in the present device the operators are required to lift or move only an empty tray or carrier; and to economize 25 time and space in the work room by an arrangement of devices which is more compact and permits the same amount of work to be done in less time and in smaller ground area.

30 Further objects of the invention are in part obvious and in part will appear more in detail hereinafter.

The invention comprises the construction and arrangement of parts hereinafter described and claimed.

In the drawings, which represent several embodiments of the invention, Figure 1 is a side elevation of one form of device applied to a flat work ironer; Fig. 2 is a plan view thereof, the ironer being omitted; Fig. 3 is a sectional elevation on the line 3—3, Fig. 1; Fig. 4 is a detail section on the line 4—4, Fig. 1; Fig. 5 is a side elevation of a portion of another form of device embodying the invention, and including tray lifting devices; Fig. 6 is a sectional elevation on the line 6—6, Fig. 5; and Fig. 7 is a diagrammatic view, illustrating another modification.

50 The invention may be applied to any form of flat work ironing machine, irrespective of its size, mechanical arrangement, number of rolls or other features. For purposes of illustration the drawings show only the entering end of a flat work ironing machine

embodiment a suitable frame 1, the concave heated ironing chest 2, the first pressure roll 3, and a traveling apron 4 to which the work is fed by the operators and which delivers it between the roll 3 and concave chest 2. 60

In the ordinary operation of such a machine the work, such as table cloths, sheets or the like, is hung over the bars or horses, which are carried loaded to the machine and laid in notches in the frame at the entering end of the machine, so that the operators can lift the work from said bars and feed it to the machine. Such bars, and the supports of the machine therefor, may be omitted when the present invention is used. 70

The present invention comprises a suitable frame work 10, which may be of any suitable form and, as shown, consists of upright side standards 11, which may be angle irons connected by suitable cross braces 12. Attached to said standards are upper and lower guide-ways or tracks, marked 13 and 14 respectively, which may also be angle members with their vertical flanges secured to the standards 11 and their horizontal flanges 15 extending inwardly therefrom. Said guide-ways may be located at any suitable elevation, but preferably the lower guide-way is at about the level of the apron 4, while the upper guide-way may be a foot 85 or so above the lower guide-way.

The work to be ironed is laid, hung or otherwise arranged upon trays or carriers 16, which may be of any suitable form, but preferably are narrow, not more than about 90 12 inches in width, to economize space. Several duplicate trays or carriers are used with each machine, each of them comprising a sheet metal body 17 in the form of an inverted shallow pan provided at its opposite ends with two or more feet 18 having anti-friction devices, such as balls or rollers 19, rolling on the horizontal flanges 15 of the guide-ways, and being also provided on their ends with endwise projecting anti-friction devices, such as balls or rollers 20, which travel between the vertical flanges 21 of the guide-ways. 95 100

The lower guide-way 14 is long enough to accommodate several trays or carriers, 105 say two, three, four or more, it being the intention to load the trays with work to be ironed while in position at the outer ends of said guide-ways, and then advance them in order along the guide-ways to the position 110

from which the work is fed to the machine. The outer ends of both the upper and lower guide-ways are provided with stops 22, which may, for example, be inwardly bent portions of the vertical flanges of said guide-ways. These stops prevent the trays from accidentally escaping. The two lower guide-ways are also provided near their outer ends with additional stop devices 23, shown as short arms hinged at 24 to the upper edge of the guide-ways. The space between said stops and the end stops 22 is sufficient to receive one tray and as each tray is filled it is pushed forward past the stops 23 which are then dropped down to prevent the tray from moving back, leaving a vacant space at the outer ends of the guide-ways to receive the next empty tray.

The inner end of the lower guide-way is closely adjacent to the ironing machine, and a portion thereof marked 14^a, is rigid and immovable and is provided at its inner end with stops 25 to prevent the trays from running into the ironing machine and with hinged stops 25^a to prevent the trays from moving backwardly or away from the ironing machine. This portion of the lower guide-way forms the feeding station at which each tray is held while the work is fed therefrom to the ironing machine. Just back of the feeding station the two members of the lower guide-way, one on each side, are provided with movable portions 26, which can be opened to allow the operators 23, to pass through the guide-ways, as will appear. These movable portions 26 may be detachable for this purpose, but are shown as hinged at 27 on vertical axes to the solid members of the guide-ways 14. The lower flanges of said hinged members are cut off on an incline, as at 28, to abut similar inclined portions of the stationary guide-way members 24, which are provided with bottom plates 29 to support the hinged members 26 when in closed position. A suitable latch 30 may also be hinged to each stationary member 14^a for locking the gates 26 in closed position. Closely adjacent to the hinges 27 the lower guide-way members are provided with hinged stop devices 31 of the same form as the stops 23 shown in Fig. 3 for preventing the trays on the lower guide-ways from advancing when the gates are open.

The upper guide-way 13 is shorter than the lower guide-way, as it is intended to accommodate only empty trays while passing the same back to loading position. It terminates short of the ironing machine, leaving a gap 32 between said guide-way and the machine.

In use of the apparatus described, let it be assumed that one tray is at the feeding station 24 between stops 25 and 25^a, that one or more loaded trays are on the lower guide-ways between the stops 23 and 31, and

that an empty tray is being loaded at the loading position at the outer end of the lower guide-way. The operators open the gates 26 and step into the frame if necessary, to more readily feed the work from the advance tray at the feeding station to the ironing machine. As soon as the advance tray is emptied they step out of the frame, lift stops 25^a and elevate the empty tray from the station 24 up through the gap 32 to the upper guide-way 13. The gates 26 are then closed, locks 31 are lifted and the next loaded tray is rolled forward to the feeding station 24 and held there by dropping the stops 25^a. The operators at the outer ends of the guide-ways also lift the latches 23 and advance the tray which they have just loaded. The feeding operators then open the gates 26 and proceed to feed the work from the new tray to the ironing machine, while the loading operators lift down another empty tray from the upper guide-ways to loading position and proceed as before.

This device enables the trays to be loaded and passed to and from the feeding position with a minimum amount of effort. Whereas in the prior machines the bars or horses were loaded at various points and carried to the ironing machine, the present invention enables the entire feeding and loading operation to be carried on in a restricted amount of space. Furthermore the operators never have to lift a loaded tray but merely roll the same in the tracks to working position. The trays themselves can be made very light and are lifted by the operators only when empty.

Figs. 5 and 6 show another embodiment of the invention in which means is provided to assist the operators in lifting the empty trays. In this arrangement one portion of the lower guide-way is made in the form of an elevator or carrier which can be elevated for lifting the trays. This carrier comprises two movable portions 35 of the lower guideway, which may be connected by cross braces 36, and which are provided with depending legs 37 sliding in suitable vertical guides on the stationary supports 38. The carrier is raised by any suitable means, such as a foot treadle 39 attached to a cross shaft 40 journaled in stationary supports 41 on the floor. There may be two such levers 39, one at each side of the machine for operation by either or both of the operators. To each lever is connected a link 42 pivoted to one arm of a lever 43, whose other arm is connected by a link 44 to one of the legs 37 of the elevator. The parts 35 of the lower guide-way, which are carried by the elevator, are closely adjacent to the ironing machine and form the feeding station at which the tray is supported while feeding the work. In this form of the invention the upper guide-way 13^a, extends

farther toward the ironing machine than in the form before described, and the portion of the upper guide-way marked 45 is connected by rigid straps 46 to the lower guide-way to form a double gate 26^a, whose hinges are indicated at 47.

With the arrangement just described an elevator with the empty tray thereon is lifted by operation of the treadle mechanism when the gates 26^a are closed, and the empty tray is run back upon the upper guide-way. The elevator is then dropped and the loaded tray advanced to position thereon. The gates are then opened and the operators step in to feed the work to the ironing machine.

Fig. 7 illustrates diagrammatically another arrangement in which the tracks or guide-ways 50 are parallel to the entering end of the ironing machine 51, instead of normal thereto, as in the forms before described. The trays 52 also roll endwise along said guide-ways; the same rails serving to support both ends of the trays. The return guide-ways 53 may be above the delivery guide-ways, as in the forms before described but are shown as at the same level and spaced horizontally therefrom. This arrangement dispenses with the hinged gates of the other forms and the two sets of guide-ways may be of equal length, although this is not essential. Other modifications will also occur to those skilled in the art.

35 What I claim is:—

1. Apparatus for feeding work to a machine, comprising a frame, two sets of guide-ways thereon spaced from each other and lying at different levels, one of said guide-ways leading to the machine and having loading and feeding stations at the same level, and work carrying devices movable on said guideways from station to station, the other of said guideways serving to return said devices to the loading station.

2. Apparatus for feeding work to a machine, comprising a frame, two sets of guide-ways thereon spaced from each other and lying at different levels, one of said guide-ways leading to the machine and having loading and feeding stations at the same level, and work carrying devices movable on said guideways from station to station, said guideways being provided with a movable portion adapted when opened to permit the

operator to enter the frame for feeding the work from said devices to the machine.

3. Apparatus for feeding work to a machine, comprising a frame, two sets of guide-ways thereon spaced from each other and lying at different levels, one of said guide-ways leading to the machine and having loading and feeding stations at the same level, work carrying devices movable on said guideways from station to station, said guideways being provided with a movable portion adapted when opened to permit the operator to enter the frame for feeding the work from said devices to the machine and means operable at will for elevating said devices from the lower to the upper guideways.

4. Apparatus for feeding work to a machine, comprising a frame, two sets of guide-ways located at different levels, the lower 75 guideway having a loading station at one end and a feeding station at the other end adjacent said machine, and work carrying devices movable on said guideway from the loading to the feeding station, the upper 80 guideway serving to return said devices to the loading station.

5. Apparatus for feeding work to a machine, comprising a frame, two sets of guide-ways located at different levels, the lower 85 guideway having a loading station at one end and a feeding station at the other end adjacent said machine, and work carrying devices movable on said guideway from the loading to the feeding station, the upper 90 guideway serving to return said devices to the loading station, said lower guideway having a hinged gate near its feeding station adapted when opened to allow the operator to enter the frame and feed work 95 from said devices to the machine.

6. Apparatus for feeding work to a machine, comprising a frame, two sets of guide-ways located at different levels, the lower guideway having a loading station at one 100 end and a feeding station at the other end adjacent said machine, and work carrying devices movable on said guideway from the loading to the feeding station, the upper 105 guideway serving to return said devices to the loading station, and means operable at will for elevating said devices from the lower to the upper guide ways.

In testimony whereof I affix my signature.
EDWIN LICHTENSTEIN.
